VOICE FREQUENCY RINGER

Walter Brandt, Jersey City, N. J., assignor to
Federal Telephone and Radio Corporation, New
York, N. Y., a corporation of Delaware

Application February 21, 1945, Serial No. 579,126

11 Claims. (Cl. 179—84)

1

This invention relates to signalling as exemplified in voice frequency ringing circuits. It has been found advantageous in various types of communication system to employ an A.-C. frequency for ringing or other signalling which lies within an important portion of the voice frequency range. The currents for both voice and signalling traverse the same path to some extent. In case of carrier systems, it is feasible to make the application of signalling frequency currents at a transmitting point directly to the transmitting branch. In doing so, however, there may be involved in some cases, the disadvantages of providing means for detuning the carrier oscillator in that branch.

An object of the present invention is to provide a signalling system wherein, the case of a two-branch channel terminal between a trunking office and a carrier frequency line, the oscillator of the receiving branch is detuned under control of the low frequency signal-control current from the office, and the currents of altered frequency are applied over the remaining portion of the receiving branch and thence through the hybrid coil to the transmitting branch and there treated and transmitted in the same manner as voice currents.

Another object is to provide at a receiving point an arrangement for separating signalling or ringing and voice currents as they are received over a common circuit without altering such circuit.

A related object is to co-ordinate the transmitting and receiving signalling arrangements for proper operation in a two-branch trunking terminal of the type above mentioned.

A further object is to provide a discriminator capable of translating effectively, the signalling current energy in the voice frequency range as received over a common circuit into a ringing control form and suppressing the effect for that purpose of voice currents received thereover.

Further objects and a better understanding of the invention may be derived from the following description of an embodiment thereof taken with the accompanying illustrative drawing.

In the drawing, Fig. 1 shows diagrammatically one embodiment of my invention as applied to a two-way terminal between a trunk office and a carrier line in a telephone system, and Fig. 2 shows in similar manner a modified form of the receiving and discriminating portion.

Referring to Fig. 1 of the drawing there is shown a two-branch terminal which in its general aspects is conventional. To this my invention has

been applied in such a way that the one direction signalling or ringing current is transmitted over one branch and in the opposite direction it is received and translated into signal controlling form in the other branch. For the purpose of this invention, it is not necessary to describe the terminal in detail. In the application of my invention, the incoming trunk from an office, transmits a control signal which, for example 5 may be alternating current of 20 cycles per second. Bridged across this incoming line is an A.-C. relay REL1. Contact R11 of this relay, controls the continuity of the incoming line at a point on the terminal side of the bridge. At 10 the demodulator in the receiving branch B, contact R12 controls the continuity of the primary winding of the output transformer of this demodulator while contact R13 controls continuity of the neutral line in the demodulator so that 15 by a change of this contact, a secondary winding 20 of the transformer, coupling oscillator 2 to the demodulator, is switched from said neutral circuit to the half of the primary winding which is not controlled by R12. In this way the demodulator is unbalanced and the output of oscillator 25 2 is applied in series with the said half of the primary of the output transformer. Contact R14 of 30 said relay REL1 controls a variation of capacitance in the tank circuit of oscillator 2 so as to alter its frequency to a point where it may be used for producing the modulation in accordance with the desired signalling, for example, in the order of 2500 cycles per second.

The operation of the circuits thus far described 35 are as follows: Upon the application of the low voltage control current from a 20 cycle office source to relay REL1, this relay opens its contacts R11 to break connection to the office trunk and unbalance the hybrid coil. It also opens 40 contacts R12 and switches contacts R13 from back to front, whereby the coupling transformer has its second winding switched to transmit oscillations from oscillator 2 through the output transformer. At contacts R14 the frequency of oscillator 45 2 is changed. Accordingly, oscillations at the desired signal frequency are transmitted through a low pass filter, a receiving amplifier and over transformer TR through the unbalanced hybrid coil and over branch A where they serve 50 to modulate the oscillations from oscillator 1 in exactly the same manner as voice frequencies produce modulation. This modulated energy is passed along the branch A and out to the high frequency line through the direction filter.

55 The receiving portion of my invention is con-

stituted as follows: The output transformer TR has an additional secondary winding. This serves to couple the conventional receiving branch path over contacts R15 of relay REL1 to a receiving discriminator arrangement RD. In the form shown in Fig. 1, this arrangement comprises a thermionic tube which as shown is a pentode, although it could be of other adaptable construction. This tube has the usual biasing parallel arrangement C2—R2 and the control grid is coupled back over the capacitor C1 to said additional secondary winding. The tube is provided with an output circuit which is connected across an additional grid, such as a screen grid, and the anode. Across this circuit is bridged relay REL2. This circuit is extended also to a network which may be properly termed the discriminator itself. Across this extended circuit is bridged in series connection an L—C loop circuit L1—C5 and a large resistance R3. That portion of the circuit across the loop is extended via rectifiers, D1, D2 and resistors R4, R5 in the respective conductors, and across this extension a resistance-capacitance network consisting of resistances R6, R7 in parallel with capacities C6, C7 is bridged. The intermediate points of the series capacities and series resistances are connected to that terminal of R3 remote from the loop circuit. Connection is extended from the high potential point of R6—C6 by way of a feed-back circuit through resistor R1 to the control grid of tube T.

The operation of the last mentioned circuits is as follows: Assume that an incoming wave traversing the direction filter carries a modulation in the voice range. In normal telephonic transmission it will traverse a band pass filter in branch B and, by the joint operation of oscillator 2 and the demodulator, said incoming wave will be demodulated and the modulating frequency component will be transmitted through a low pass filter and a receiving amplifier and thence through the hybrid coil and over contacts R21, R22 to the office trunk. During this operation it is assumed that none of the contacts of relay REL1 have been changed from their normal positions.

Accordingly some of the energy present at transformer TR will pass by way of the additional secondary winding of the receiving discriminator RD and be impressed on the control grid of the tube T. In its normal condition, this tube does not pass sufficient plate current to energize relay REL2. When, however, such incoming wave is constituted essentially by a single frequency signalling wave, some of the energy after demodulation will be impressed on and amplified by the amplifier, and the output therefrom, in turn, will be impressed across the above described loop-resistance bridge connection. If the L—C circuit, L1—C5, is tuned to the frequency of this incoming signalling wave, it offers a high impedance thereto and energy at this frequency is thereupon rectified in rectifier D1, and the direct current potential is impressed through resistor R4 on the high potential point of the R6—C6 combination. From that point it is transmitted by way of the feed-back FB to the control grid. In this manner the tube produces sufficient amplification to energize relay REL2. Should, however, the demodulation energy contain waves of other frequencies than the signalling wave, such as those in the usual voice band, a different operation takes place at the discriminator. In that event, the L—C cir-

cuit offers only a low impedance while R3 offers a high impedance so that the energy produced by a resistance drop in R3 is rectified by rectifier D2 in a proper direction so that a D.-C. potential appearing across the combination R7—C7 will be of the polarity opposite to that produced in case of the single frequency thereby producing by way of the feed-back a sufficiently negative biasing potential for maintaining relay REL2 inoperative.

In the first assumed case, the demodulated ringing or single frequency signal by operating relay REL2 shifts contacts R21, R22 so as to break the connection of the incoming office trunk to the hybrid coil and apply low frequency control current to said office trunk for indicating the incoming signalling or ringing operation. It will be noted also that the shifting of contacts R21, R22 prevents the direct application of the ringing or signalling current itself to the office trunk line.

In case mixed frequencies in the voice range are impressed on the discriminator a small portion of their energy will be passed by way of rectifier D1 to the positive terminal of R6, C6 combination. The amount of this energy, however, is small compared to that which will be passed by rectifier D2. By choosing resistor R4 to be greater than resistor R5 the D.-C. voltage developed across said resistor-condenser combination is smaller than the voltage across the R7—C7 combination. It will be seen, therefore, that all the frequencies in the received band other than the particular signalling frequencies counteract the effect of this particular signalling frequency and that it is only in the absence of such other frequencies that the incoming particular signal frequency can make the grid sufficiently positive to operate relay REL2. It is to be additionally noted that a desired time delay can be effected by a proper choice of values among the elements R4, R5, R6, R7, C6 and C7. Furthermore, the feed-back arrangement offers the advantage of increased sensitivity and reliability in the operation of the discriminator.

In Fig. 2, I have shown a receiver discriminator RD' which is modified from that in Fig. 1. This discriminator comprises in general, an amplifying tube A and an input therefor consisting of a three-terminal network which somewhat resembles a parallel-T-bridge. The tube output comprises a rectifier and the relay REL2. The connection to the network from branch B of the terminal by way of transformer TR is like that in Fig. 1. Between its upper two terminals C and D, this network has two paths. One comprises a narrow band-pass filter consisting of a series resonant circuit F1 and an anti-resonant circuit F2; the other path comprises an anti-resonant circuit F3 and a rectifier E so poled as to pass only the negative half waves. The return circuit of anti-resonant loop F3 is by way of resistance L, of low value which acts as a load for said loop circuit F3. The return from the opposite pole of the rectifier is by way of the high resistance M which acts as a D.-C. path for the rectified current and also, along with a parallel capacity C9, constitutes a delay circuit.

The operation of this modification is as follows: Normally, the bias of tube is such that it does not pass enough plate current to operate the relay. If the incoming energy is essentially only that of a particular signalling frequency to which the above described resonant circuits are tuned, then substantially all this energy is passed by the

above described narrow band-pass filter without traversing the rectifier and is applied to the grid of the tube in such a way as to materially increase the flow of plate current and, thereby, operate relay REL2. In case, however, the incoming energy is of various frequencies in the voice band, they are largely transmitted over the second path above described and are rectified by the rectifier E, thereby, producing a D.-C. potential at the terminal of resistance M which is so far negative as to prevent the operation of the tube to supply sufficient plate current for operation of relay REL2.

What I claim is:

1. Apparatus for transmitting signals in opposite directions over a two branch trunking circuit having hybrid coil connection at one end for low frequency and direction connection at the other end for high frequency and an oscillator for each branch, comprising means responsive to control currents to alter the tuning of the receiving branch oscillator to produce signalling currents of voice frequency, means for transferring said signalling currents to the transmitting branch, means for receiving over the direction connection incoming current energy and for demodulating it under control of the receiving branch oscillator into signals of voice frequency range, and circuit means normally connected to the receiving branch for discriminating between control current and voice frequency signalling currents.

2. Apparatus according to claim 1 wherein said means responsive to said control currents conditions the hybrid coil for transferring said signalling currents and disabling the discriminator means.

3. Apparatus according to claim 1 wherein said means responsive to said control currents includes means for unbalancing the demodulator and establishing a path for oscillations from the oscillator to the outgoing end of the receiving branch.

4. A signalling apparatus having a two-branch telephone trunking circuit having an oscillator in a transmitting branch and an oscillator in the receiving branch, means responsive to control currents to alter the tuning of the receiving branch oscillator to produce signalling currents of voice frequency, means for transferring said signal currents to the transmitting branch to control the energy of the transmitting oscillator and means for transmitting said controlled energy.

5. A signalling apparatus according to claim 4 wherein the hybrid coil connects the two branches to the line carrying the incoming control currents, and the responsive means conditions the hybrid coil for said current transferring.

6. A signalling apparatus comprising a line transmitting a band of low frequency alternating currents, a bridge thereacross including in series a loop circuit anti-resonant to substantially a single frequency in said band and a resistance, a thermionic relay coupled to said line, means for biasing said relay to control its operation including means for translating thereto differentially the band and the single frequency energies respectively as determined by said bridge.

7. A signalling apparatus according to claim 6 wherein the translating means includes a rectifier for determining the polarity of the biasing means.

8. A signalling apparatus comprising a line transmitting a band of low frequency alternating currents coupled to the input of a thermionic relay, an output circuit for said relay, a bridge thereacross including in series a loop circuit anti-resonant to substantially a single frequency in said band and a resistance, means for rectifying selectively the low frequency energies across the anti-resonant loop and resistance, and means for combining their direct current products to bias the tube for selective operation.

9. Apparatus according to claim 8 having means for differentially combining the direct current energies.

10. A signalling apparatus comprising a line transmitting a band of low frequency alternating currents, a frequency discriminating network comprising a band filter passing substantially only a single frequency with further means for passing with little attenuation frequencies of said first mentioned band other than said single frequency, said network including means for deriving from said frequencies a direct current potential, a thermionic relay connected to said network and means for selectively controlling operation of the thermionic relay in accordance with the output energy of said filter and said further means.

11. Apparatus according to claim 10 wherein the network includes an impedance bridge across said line having in series a loop anti-resonant to said single frequency and a resistance.
